(57) CLAIM

The ornamental design for a handbag as shown and described.

DESCRIPTION

1. Handbag

1.1 is a perspective view of a handbag, showing the new design;

1.2 is another perspective view thereof, with the shoulder strap shown in an alternate position;

1.3 is a front view of the design of the handbag of 1.1, with the shoulder strap shown in the position of 1.1;

1.4 is a rear view of the design of the handbag of 1.1;

1.5 is a top view thereof;

1.6 is a bottom view thereof; and

1.7 is a right side view thereof.

The thicker broken lines shown crossing claimed surfaces depict stitching and form no part of the claim. All other (thinner) broken lines depict portions of the article and form no part of the claim.

1 Claim, 7 Drawing Sheets
